Samuel H. Gibbs of Albany, N.Y.
Letters Patent No. 4815. Dated May 15, 1866.
Design for the Plate of a Parlor Stove.

It is desired to have a copy of the letters Patent and a copy of the design for the plate of a parlor stove.

It is desired to have it as follows:

I, Samuel H. Gibbs, of Albany, State of New York, have invented or produced a new and original design for the plate of a parlor stove, and do hereby declare the following is a full and exact description of the same, reference being had to the accompanying photographs.

A symmetrical design for the arms

R	"	"	"	"	ends
G	I	"	"	"	back of arm
B	"	"	"	"	front of arm

Together forming plates for parlor stove "box"

It is desired to have a copy of the letters Patent and a copy of the design for the plate of a parlor stove, and described.
